James G. Hamilton

JAMES G. HAMILTON, OF CHICAGO, ILLINOIS.

Letters Patent No. 87,772, dated March 16, 1869.

IMPROVEMENT IN STEAM-GENERATORS.

The Schedule referred to in these Letters Patent and making part of the same.

To whom it may concern:

Be it known that I, JAMES G. HAMILTON, of Chicago, Cook county, Illinois, have invented certain new and useful Improvements in Superheated-Steam Generators; and I do declare that the following is a full, clear, and exact description thereof, reference being had to the accompanying drawings, making part of this specification, in which—

Figure 1 is a longitudinal section.

Figure 2, an end view, with the head B partially removed.

Figure 3 is a detached view of deflectors.

The object of my invention is to so construct superheated-steam generators, that the steam shall be carried, when, and as it is formed, to and along the interior surface of the generator, in a current tending steadily in one direction, that is, from the point at which the water is delivered, to the point at which the steam finds an outlet, thus causing a constant and rather rapid transmission of heat away from the iron or other metal of which the generator may be made, and so preventing or retarding the injury which the generator would suffer from the fire, if the heat were, as it otherwise would be, less constantly, regularly, and rapidly transmitted, or carried off.

To enable others skilled in the art to make and use my invention, I proceed to describe its construction and operation.

A A represent the cylinder, and

B B', the heads of a generator, constructed in the manner I suggest.

D represents the pipe, through which the water is conveyed into the generator, and from which it is injected through numerous small holes, near the end of said pipe, into the chamber G, where it is instantly converted into superheated steam.

E is the outlet pipe, for the steam, and

F, the blow-off pipe, through which any accumulation of water may be blown off.

There is no peculiarity in the construction of these parts, except that the openings in D, through which to inject the water in small jets, are all or nearly all placed near enough the end of the pipe D, at f, to be within the chamber G.

Within the generator, I place two diaphragms or deflectors, a b, one near each end thereof, the diameter of which is somewhat less than that of the interior of the generator, so as to permit the steam to pass from G to H, and from H into the outlet-steam pipe E.

These deflectors may be made either plane or more or less convex, or somewhat conical. If not plane, the convex surface should be placed toward the steam-outlet E. This is desirable, in respect to a, in order to give sufficient room in the chamber G to receive so much of the end of water-pipe D as may be needed to furnish apertures enough for the discharge, into said chamber G, of the requisite quantity of water for the production of steam.

In a generator of fifteen-horse power, the deflectors should be so placed that the edge of each will be near the flange h, and also near the interior surface of the cylinder A A, say about an inch distant, more or less, according to the convenience with which said deflectors may be inserted and secured to the flanges h h h, by means of the stay-bolts or screws e, or in some other suitable manner.

The deflector b is supported by means of strips of iron or other metal, d, fig. 2, radiating from near the outlet-steam pipe E, to or near to the flange h, one edge of which strips rests against the inner surface of the end, B, while the deflector rests against the other edge. Other supports may be used for this purpose.

c is an iron, or other metallic tube, surrounding the pipe D, closely fitting between the two deflectors, and furnishing a central stay to the deflector a.

The water-injecting pipe D passes through both deflectors, the end, f, extending into the chamber G formed by and between the deflector a and the end, B', of the generator.

Only into this chamber G should all or nearly all the water be admitted, and that in small jets, through little holes in or near the end of said water-injecting pipe D.

In this chamber, steam is first formed, as the water is delivered in comminuted jets from the pipe D. In seeking to escape, it is compelled to travel from the centre of the chamber G, around the outer edges of the deflectors a and b, to reach the outlet-pipe E, thus passing a steady current along the interior surfaces of the head B', the cylinder A A, and the head B, and so rapidly transmitting the heat, and retarding the injury that would otherwise accrue to the iron from a longer retention of the heat, as before herein set forth.

As generators are now constructed by others, without the deflectors and their appendages, as I have herein set forth, most of the water, it is true, is delivered near the ends of the pipe, as at f, yet portions of it are delivered at various points along the pipe D, between the ends or heads B and B'.

As soon as formed, the steam naturally seeks to escape by the most direct route to the outlet-pipe E, thus forming no current, or but a slight and irregular one, near or next to the ends and sides of the vessel, which are hence left to suffer from the retention, for a longer or shorter period, of heat, which, by means of the apparatus which I have devised, and which I herein describe, would be transmitted regularly and rapidly along the interior surface of the vessel, and away from it, after having performed its office of converting the jets of water or spray into superheated steam.

Indeed it is believed that much of the steam which is first formed, as generators are now made by others, remains imprisoned, and more or less inactive, in the parts of the vessel remote from the injecting-pipe, as long as the machinery continues in motion, much of the more newly-formed steam, first finding the outlet

from being nearer thereto, while the old continues to remain in the vessel, to at least a considerable extent.

When the deflectors are but little larger in diameter than the openings in the heads or ends, they may be made and inserted entire, by clipping the outer edges at two opposite points, as shown in fig. 3.

When the opening in the ends of the vessel is relatively much smaller than the deflectors, the latter may be made in halves, or smaller fractional parts of a circle, and inserted separately, and properly put together within, and secured in a variety of ways, which will readily suggest themselves to a mechanic.

By the use of my improvement, the objections as set forth to the use of the generator, as at present constructed, are obviated.

The object of my invention can be partially accomplished by the use of either deflector alone, but I recommend the use of both, as more fully accomplishing the object.

Having thus fully described my invention, What I claim as new, and desire to secure by Letters Patent, is—

1. The chamber G, substantially as set forth.
2. The deflectors *a* *b*, constructed substantially as specified.

JAMES G. HAMILTON.
